Willie Fowler.
ATTORNEYS

UNITED STATES PATENT OFFICE.

CARL MACK, OF LONG ISLAND CITY, NEW YORK, ASSIGNOR TO MACK LOCK COMPANY, INC., OF LONG ISLAND CITY, NEW YORK, A CORPORATION OF NEW YORK.

VEHICLE DOOR-LOCK CASING AND COVER.

Application filed January 17, 1923. Serial No. 613,175.

To all whom it may concern:

Be it known that I, CARL MACK, a citizen of the United States, and resident of Long Island City, in the county of Queens and

5 State of New York, have invented certain new and useful Improvements in Vehicle Door-Lock Casings and Covers, of which the following is a specification.

My invention relates to an improved door-lock casing and cover plate therefor and which is particularly well adapted for use with locks for doors of automobiles or other vehicles, steam-ships, motor boats, yachts, or houses, in places where a simple and 10 strong lock is required. One of the objects of the invention is to eliminate the usual brazing, riveting and soldering of the various parts carried by the casing, and to that end I make the main or front plate or casing 15 and the various supports, lugs and guides for the locking-bolts and their operating mechanism, all in one piece of material. Another feature of my invention is the provision on the said casing of means for supporting or holding the escutcheon or cover plate which furnishes a suitable recess for and guards the operating lever of the bolt-actuating mechanism; the present practice being to secure the escutcheon plate to the 20 door, separately from the lock casing and considerable time is thereby lost in obtaining the correct and true position of the said plate, and, moreover, the slightest shifting out of place of said plate will materially interfere with the proper working of the lock.

There are other advantages possessed by my novel construction and arrangement of the said two parts which house the locking bolts and their operating mechanism, as will 25 appear from the following description and the accompanying drawings illustrating my invention and wherein;

Figure 1, is a front elevation of the casing, with the relative location of the cover thereon shown in dotted lines, where it overlies the same.

Figure 2, is a top-plan view of the same.

Figure 3, is a side elevation of the same, the view being taken from the side having the rim for the lock-style of the door on which the lock may be mounted.

Figure 4, is a vertical sectional view of the same, the plane of the section being indicated by the line 4—4, in Fig. 1.

55 Figure 5, is a horizontal sectional view

of the casing, shown as detached and the plane of the view being on line 5—5, in Fig. 3.

Figure 6, is an elevation of the outside of the cover shown as detached.

Referring to the drawings, the casing 1, has a flat plate-like body part with its outer end bent so as to form an inwardly projecting flange 2, which when the casing is mounted on the lock-style of a door, lies upon the face of the edge of the same opposite the keeper. The flange 2, is provided with bolt-receiving holes 3, and with screw-holes 4, for reception of attaching screws. Other screw-holes 5, are formed in the body 65 of the casing, and also perforations 6, at the inner edge for receiving attaching members for securing a finishing frame to the front of the casing, which part is not shown.

Near the upper and lower ends of the casing, I cut the material thereof at 7, 7, respectively, in such manner as to form up therefrom inwardly projecting integral lugs 10, and 11, the outer one 10, being slightly 70 longer than the inner one 11. The lugs of each pair are parallel with each other, the outer one 10, being formed with a circular orifice 12, and the inner one with a circular orifice 13, the latter being of slightly smaller diameter than the orifice 12, which is of the same dimension as the bolt-hole 3, in the flange 2, and with which hole the two orifices 12 and 13, are in axial alinement, thus providing practically three bearings for the reciprocating bolt which is carried therein 75 and which has its inner end reduced in diameter to fit in the smaller orifice 13, of the bearing lug 11. While I have not shown the reciprocating bolts which are mounted in said bearing lugs, it will be noted that 80 said bolts being reduced in diameter at their inner ends may have a shoulder thereon at such point which will take against the spring interposed between it and the outer face of bearing lugs 11, to limit the inward movement of the same when the bolts are retracted.

In order to obtain true axial alinement of the respective openings 3, 12 and 13, I bore or cut them after the lugs 85 are struck or bent up from the flat body part of the casing. The large perforation 14, near the outer edge of the casing is designed to receive a stud or member on which is mounted the operating lever of the bolt actuating mechanism which is not shown.

The cover 15, is applied to the rear side of the casing 1, and is securely fastened thereto by means of a set of rivet-posts 16, the respective ends of which pass through 5 said cover and casing and are upset against the same, as rivets, each post having at its respective ends the shoulders 17, for engaging the adjacent face of the said casing and cover in order to space them apart. The 10 casing is provided with suitable holes 18, and the cover with corresponding holes 19, for receiving the rivet-posts, the space between the two said plates being for the accommodation of the various moving parts of the 15 bolt-actuating mechanism and the operating lever.

The cover 15, has a longer dimension in the direction of the movement of the locking-bolts which are carried in the bearing-lugs 10 and 11, but is narrower in the direction at right-angles thereto, as indicated at 20, Fig. 6, and the parallel edges of said contracted part 20, are counter-sunk by taking into the notches 21, 21, formed at the 25 corner of each of the bearing-lugs 10, and 11, towards the center of the plate or casing, which counter-sinking gives the cover a firm support on the casing, in addition to the rivet-posts, and prevents any lateral shifting 30 of the cover. The cover is also provided with a large opening 22, near its outer end corresponding in size and location with the opening 14, in the casing and for the same purpose as that described for the latter, as 35 indicated in Figure 4, where it will be seen they register with each other.

The inner end of the cover 15, overhangs the inner end of the casing to a considerable extent, as indicated at 23, and sufficiently to 40 provide a recess 24, of ample size to receive the handle end of the operating-lever of the bolt-operating mechanism, not shown. The part 23, of said cover, has its overhanging edge provided with an inwardly extending 45 lip or rim 25, as an enclosure for the recess, and this is curved or bowed outwardly, while the edge of the casing lying opposite said rim, is cut away in an inward direction to make said edge re-entrant with respect to the casing, as indicated at 26, thus providing 50 a suitable opening into the recess 24, for the easy insertion of the fingers of the operator in grasping the operating-lever which lies in said recess.

55 The cover rim 25, is notched at each end at 27, for receiving the casing 1, so as to lie flush therewith, as indicated in Figs. 1 and 2, thereby affording support to the finishing frame which is mounted by fasteners which 60 take into the holes 6, on the casing, and which frame is not shown.

It will be noted that my improved lock casing and cover and the various supporting means and bearings for the pair of bolts, 65 provide both a simple and a strong con-

struction and that the same may be made at a comparatively low cost from sheet steel, or duralumin or other suitable material, which can be readily cut to size and shape, and formed up by means of suitable dies 70 into finished form. The lugs which provide the two spaced bearings for each bolt, being integral with the body of the casing, give especial strength to the mounting of said bolts, without liability of the bearings getting out of alinement. 75

Having thus described my invention, what I claim and desire to secure by Letters Patent is:—

1. A door-lock casing and cover therefor, 80 comprising a main front-plate provided with a flange formed with bolt-receiving holes and disposed so as to lie on the edge of the lock-style of the door, and having inwardly projecting lugs or ears provided 85 with bolt-receiving bearings for the reciprocating bolts, a cover or back-plate adapted to be mounted on said main plate with a space between the two for receiving the bolts and the operating mechanism, said 90 cover projecting beyond the inner edge of said main plate and overhanging the same at the rear edge, said cover having its overhanging end provided with an inwardly projecting rim so as to provide a recess for the 95 reception and movement of the operating-lever of the bolt-operating mechanism to which access is had by the operator through the opening provided between said rim and the rear edge of said main-plate. 100

2. A door-lock casing and cover therefor, comprising a main front-plate provided at its outer end with a door lock-style flange and formed with inwardly projecting integral lugs or ears provided with bolt-receiving bearings arranged in axial alinement with bolt-receiving holes formed in said lock-style flange, the rear edge of said main plate being cut away inwardly and reentrant thereof, a cover or back plate adapted to be mounted on said main plate with a space between the two for receiving the reciprocating bolts and the operating mechanism, said cover plate having an extension at its inner end overhanging the cut away edge of the main plate and provided with an inwardly projecting rim and providing in conjunction with said main plate a recess for the reception and movement of the operating-lever of the bolt actuating mechanism to which access is had by the fingers of the operator through the opening constituted by the cut-away edge of said main plate and the rim of said cover. 110

3. A door-lock casing and cover therefor, 115 comprising a main front-plate provided with a door lock-style flange having bolt-receiving holes, inwardly projecting lugs arranged in pairs on said plate with the pairs suitably spaced apart and the opposing edges of the 120

lugs of each pair being formed with notches or counter-sinks, a cover mounted on said casing and counter-sunk in said notches of the bolt-carrying lugs and overhanging the inner end of said casing to provide at such place a recess for the reception of the operating-lever of the bolt-operating mechanism.

4. A door-lock casing and cover therefor, comprising a main front plate provided with a door lock-style flange having bolt-receiving holes and bolt-bearing lugs, a cover

mounted on said casing with a space between the two, the inner end of said cover overhanging the inner end of said casing and provided at its inner edge with a rim provided at its ends with counter-sinks for receiving the adjacent edge of said casing to bring the two parts flush with each other. 15

Signed at New York, in the county of New York and State of New York, this 20 16th day of January A. D. 1923.

CARL MACK.
